UNITED STATES PATENT OFFICE.

HARRY TUSTIN THOMAS, OF BALTIMORE, MARYLAND, ASSIGNOR TO JOHN A. DOBSON AND COMPANY, OF SAME PLACE.

DESIGN FOR A JEWEL-CASE OR SIMILAR ARTICLE.

SPECIFICATION forming part of Design No. 34,527, dated May 21, 1901.

Application filed April 25, 1901. Serial No. 57,506. Term of patent 3½ years.

To all whom it may concern.

Be it known that I, HARRY TUSTIN THOMAS, a citizen of the United States, residing at Baltimore, State of Maryland, have invented and produced a new and original Design for a Jewel-Case or Similar Receptacle, of which the following is a specification.

Reference is to be had to the accompanying drawings, in which—

Figure 1 is a side elevation of the jewel-case or similar receptacle embodying the design. Fig. 2 is a front view of the same.

The design consists in the shape and configuration of the jewel-case or similar receptacle illustrated in the accompanying drawings, in which the bottom of the case is the miniature representation of a sleigh, comprising a body *a*, provided with an undulating upper edge *b*, and also provided at its front with bead-like

formations *c* and two runners *d*, which curve 20 downwardly and outwardly from the lower side of said body, and the top of the jewel-case is a representation of a human figure *e*, bundled up to the shoulders in lap-robés *f* and seated in the body of the sleigh. 25

The essential features of the design are the bottom, which is a representation of a sleigh, and the top, which is a representation of a human figure seated in the sleigh.

I claim—

The design for a jewel-case or similar receptacle herein shown and described.

In testimony whereof I affix my signature in the presence of two witnesses.

HARRY TUSTIN THOMAS.
